(57) **CLAIM**

The ornamental design for a tire for automobiles, as shown and described.

DESCRIPTION

FIG. 1 is a front, right perspective view of a tire for automobiles, showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and,
FIG. 7 is right side elevation view thereof.

The portions of the tire depicted in long broken dashed lines of even length form no part of the claimed design.
